UNITED STATES PATENT OFFICE.

THOMAS ISAAC WESTON, OF COLUMBIA, SOUTH CAROLINA.

SEPTIC TANK FOR SEWAGE DISPOSAL.

1,120,351.

Specification of Letters Patent.

Patented Dec. 8, 1914.

Application filed July 11, 1914. Serial No. 850,390.

To all whom it may concern:

Be it known that I, THOMAS I. WESTON, a citizen of the United States, residing at Columbia, in the county of Richland and State of South Carolina, have invented a new and useful Septic Tank for Sewage Disposal, of which the following is a specification.

The present invention appertains to a septic tank for sewage disposal, and aims to provide a novel and improved apparatus of that character for domestic use in rural or isolated districts for the hygienic and convenient disposal of the sewage.

15 The invention contemplates the provision of a sewage disposal apparatus which may be inexpensively manufactured at a central plant by skilled labor and shipped to the purchaser in a rural or isolated district, 20 whereby the apparatus may be readily set up by the purchaser, even though he be unskilled, and whereby no special machinery will be necessary in installing the apparatus.

Another object of the invention is to provide a septic tank of unique construction and which will be improved generally, to enhance the utility thereof, and to render the apparatus most hygienic, practical and efficient in its use.

30 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

40 The invention has been illustrated in its preferred embodiment in the accompanying drawing, wherein:—

Figure 1 is a vertical median section of the apparatus assembled, and Fig. 2 is a horizontal section of the apparatus taken on the line 2—2 of Fig. 1.

45 In carrying out the present invention there are provided a pair of companion or complementary chambers 1 and 2, the first 50 of which acts as a receiver, while the other serves as a discharge chamber. Each of the chambers 1 and 2 comprises an upright cy-

lindrical shell 3, which is preferably molded from concrete or other plastic material, and which has the embedded reinforcing 4. 55 Each of the shells 3 is provided with a molded concrete bottom 5 having the embedded reinforcement 5^a and the bottoms 5 are preferably molded integral with the shells 3, although the bottoms may be molded independent of the shells and cemented thereto. 60 Each of the shells 3 is further provided with a cover or top 6 seated thereon, and preferably molded from concrete and having the embedded reinforcement 7 for 65 strengthening the same. The chambers 1 and 2, in practice, are implanted or embedded in the soil, as indicated in Fig. 1, but it is to be understood that the chambers may be arranged in different manners according to 70 the various circumstances.

The chambers 1 and 2 are disposed adjacent each other and are brought into communication by means of a pipe 8 which is engaged through suitable openings provided 75 in the adjacent walls of the chambers 1 and 2 adjacent their upper ends, the pipe 8 preferably being formed from terra cotta or tile, and having a depending inlet arm or branch 9 within the receiver or chamber 1 to provide a sealed connection between the upper portions of the two chambers.

The receiver or chamber 1 is provided with an upper inlet diametrically opposite the pipe 8, and to this end, an inflow pipe 85 10, preferably formed of terra cotta or tile, has one end engaged through a suitable opening provided in the corresponding wall of the chamber 1, and the intermediate portion of the inflow pipe 10 is provided with 90 a depending bend 11 forming a trap for preventing the escape of foul gases from the chamber 1 back through the inflow pipe 10. Mounted between the opposite side walls of the chamber 1 intermediate the inflow pipe 95 10 and the discharge pipe 8 of the chamber 1, is disposed a baffle or partition 12, which may have its ends seated within slots 13 provided in the corresponding walls of the chamber 1, or which may be molded integral 100 with the shell of the chamber 1. The baffle or partition 12 projects slightly above the normal water level of the chamber 1, and projects or extends downwardly to a suffi-

cient depth within the water, as illustrated in Fig. 1, to cause the fluid to pass downwardly under the baffle or partition 12 in passing from the inflow pipe 10, to the pipe 8. There is an opening below the partition or baffle 12, for the passage of the sewage from the inlet side of the chamber to the outlet side thereof, it being noted in this connection that the pipes 10 and 8 are in alignment immediately above the normal water level of the chamber 1, while the inlet arm or branch 9 of the pipe 8 depends below the normal water level to prevent the escape of gas from one chamber to the other and to prevent the flow of floating matter within the chamber 1 to pass through the pipe 8 into the chamber 2.

The discharge chamber 2 is provided with an outlet siphon, which embodies an upright block 14 preferably molded from concrete or other plastic material and having one side curved or formed to snugly fit that wall of the chamber 2 remote from the chamber 1. The siphon block 14 is seated upon the bottom of the chamber 2, and its upper end projects slightly above the normal water level of the chamber 1 or the axis of the pipe 8. The siphon block 14 is provided with an upright passage 15 which extends to but terminates slightly short of the upper and lower ends of the block 14, and the block 14 is provided with an inlet or intake arm 16 leading downwardly from the upper end of the passage 15 and terminating at a point above the bottom of the chamber 2, as at 17. The block 14 is further provided with an outlet or discharge arm 18 extending upwardly from the lower end of the passage 15 to the lateral opening or socket 19 provided in that face or side of the block 14 which rests against the corresponding wall of the chamber 2. The opening or socket 19 is disposed on a level or slightly below the lower end of the intake arm 16 of the siphon, while the bend defined by the discharge arm 18 of the siphon and the lower portion of the passage 15 forms a trap extending below the opening 19 and the lower end 17 of the intake arm 16. The corresponding side wall of the chamber 2 is provided with an opening 20 registering with the opening or socket 19 of the siphon block 14, and an outlet tile or pipe 21 is inserted inwardly through the opening 21 and into the opening or socket 19 to communicate with the siphon.

As will appear from the foregoing taken in connection with the drawing, the present apparatus comprises but a comparatively few number of simple parts, which may be readily manufactured from concrete, with the exception of the pipes 8, 10 and 21, and these pipes may be constructed of terra cotta or tile. The several parts may be

readily shipped to the purchaser or user, and may be conveniently set up by him without experience or skill, and without the necessity of special machinery, or forms.

In assembling the apparatus, it being noted that the shells 3 may be conveniently rolled upon the ground to the point where the sewage disposal plant is to be arranged, and then the shells may be inserted into suitable holes, or a single hole dug in the ground. After the shells 3 have been properly planted or embedded in the soil, at the proper level, according to the peculiar condition of the surface of the soil, the siphon block 14, outlet pipe 21, connection pipe 8, inflow pipe 10 and cover 6 may be applied to the respective shells as will be obvious without lengthy description. The pipes 8, 10 and 21 are preferably cemented in place within the openings in the respective shells 3, and the siphon block 14 is also preferably cemented within the chamber 2. The inflow conduit or drain (not shown) which extends from the dwelling to which the septic tank is to be connected, is connected to the inflow pipe or trap 10, and the joints of the inflow conduit or drain are preferably cemented to avoid the escape of the sewage in passing from the dwelling to the disposal plant. The seepage tile, (not shown) which are of porous material, are laid on a slight angle of inclination to communicate with the outlet pipe 21 of the chamber 2, and are preferably laid with uncemented joints and within a filling of crushed stone, gravel or other loose material. The seepage tile are preferably laid within sixteen inches below the surface of the ground, since the soil bacteria cannot thrive at a greater depth in the soil. However, if the soil is loose and well adapted to absorption, the seepage tile need only be laid in the soil at the proper depth and at a slight angle of inclination to prevent the septic liquid discharged from the tank from flowing rapidly to the end of the seepage conduit. Thus, when the seepage conduit has a fall of not more than four inches per hundred feet, the septic liquid in flowing into the seepage conduit, will be distributed uniformly throughout its length, to insure of the proper seepage of the liquid into the soil.

In operation, the sewage passing through the trap pipe 10 from the inflow conduit or drain will be discharged into the receiver or chamber 1 at one side of the baffle or partition 12, whereby the solid constituents of the sewage will be broken up or disintegrated before passing under the partition or baffle 12. The trap pipe 10 being continually filled will prevent the escape of foul gases from the receiver or chamber 1 back through the trap pipe 10 into the inflow conduit or drain, and consequently, the foul

gases will not be liable to pass back into the dwelling as would be objectionable. The solid matter flowing into the receiver or chamber 1, will be confined in the receiving side of the receiver or chamber by the partition or baffle 12, until the solid matter disintegrates or becomes heavy enough to sink. This causes the liquid and solid matter within the receiving portion of the chamber 5 to flow downwardly in a gentle manner, thereby permitting the action of the bacteria which is essential to render the solution septic. The action of the bacteria in the chamber or receiver 1 will reduce the sewage 10 to a liquid before passing into the second or discharge chamber 2, and as above indicated, the downturned or depending branch or arm 9 of the pipe 8 will prevent any floating matter within the chamber or receiver 1 15 from passing into the chamber 2, since the liquid flows into the pipe 8 below the normal water level of the receiver or chamber 1. This assures of the flow of the liquid only from the receiver or chamber 1 into the discharge 20 chamber 2. The connecting pipe 8 between the two chambers assists in the gentle mixing of the liquid to assist in the action of the bacteria, and furthermore, the pipe 8 prevents the passage of gases from 25 one chamber to the other. As a result, the second or discharge chamber 2 contains practically a liquid sewage only.

The discharge siphon of the chamber 2 enables the said chamber to be automatically 30 emptied periodically, at intervals of about one day apart, which is desirable for retaining the sewage within the tank a sufficient length of time for the proper action of the bacteria. Thus, as the discharge 35 chamber 2 becomes filled up to the pipe 8, the intake arm 16 of the siphon will become filled, as soon as the liquid level within the chamber 2 rises up to the pipe 8, it will start to flow down the passage 15 of the siphon, 40 and as a result, the siphonic action through the siphon will be started, and the liquid will thence flow from the siphon into the seepage tile, until the vacuum within the siphon is broken by the lowering of the liquid level below the inlet end 17 of the intake arm 16. In this connection it is to be 45 noted that the chamber 1 is filled by intermittent gushes or charges, whereby the chamber 2 will be similarly filled, in order 50 that after the level of the contents of the chamber 2 rises to the point illustrated in Fig. 1, the succeeding gush or charge flowing through the pipe 8 will cause the liquid to rise suddenly within the siphon, to start 55 the siphonic action. The end 17 of the intake arm 16 is spaced slightly above the outlet pipe 21, to assure of the siphonic action without relying upon the down grade of the seepage tile. Then, as the discharge

chamber 2 again becomes filled up to the 65 predetermined discharge level, the action of the bacteria from the sewage will continue for the aforesaid period, it being desirable that the sewage be discharged about once a day, to assure of the proper action 70 of the bacteria, since they thrive best when the liquid is held within the septic tank for the period indicated. Even when the discharge chamber 2 is emptied, due to the siphonic action, a sufficient amount of liquid 75 will remain in the chamber 2, due to the spacing of the intake arm 16 of the siphon above the bottom of the chamber 2, to assure of the culture of bacteria within the chamber 2 to act quickly upon the new liquid 80 introduced in the chamber 2 from the chamber 1 as the chamber 1 overflows.

Although the apparatus may be constructed in different sizes to increase or decrease the capacity thereof, the capacity of the 85 apparatus may be indefinitely increased by providing the same with a plurality of chambers or receivers 1 arranged in series, the first receiver or chamber 1 having the inflow pipe 10 connected thereto, the last 90 receiver or chamber 1 having a pipe 8 connected thereto to lead to the discharge chamber 2, and the respective chambers 1 being connected by pipes 8 similar to the connection between the chambers 1 and 2 95 illustrated. The removable covers 6 normally close the chambers 1 and 2, and may be removed at any time to enable access to be had into the chambers for purposes of cleaning, repairing or replacing the parts. 100

The present apparatus is designed and intended particularly for one family use, to be purchased and set up by those living in rural or isolated districts, and without the incurrence of great expense or trouble. The 105 other advantages and capabilities of the present invention will be obvious to those versed in the art, without further comment being deemed necessary.

Having thus described the invention, what 110 is claimed as new is:—

1. In a device of the character described, a discharge chamber having an upper inlet, an upright siphon block disposed within the chamber and fitting against one wall 115 thereof, the siphon block having a siphon passage therein, and the said wall of the chamber and the outlet end of the siphon passage having registering openings, and an outlet pipe fitted in said openings. 120

2. In a device of the character described, a discharge chamber having an upper inlet, an upright siphon block disposed within the chamber and fitting one wall thereof, the siphon block having an upright passage, an 125 inlet arm leading from the upper end of the said passage and terminating above the bottom of the chamber, an upturned discharge

arm extending from the lower end of the
passage, and an opening at the end of the
said discharge arm, and the said wall of
the chamber having an opening registering
5 with the said opening, and an outlet pipe
fitting in said openings.

In testimony that I claim the foregoing

as my own, I have hereto affixed my signature
in the presence of two witnesses.

THOMAS ISAAC WESTON.
